ELECTROLYTIC CELL AND TERMINAL
THEREFOR

Umberto Pomilio, London, England, assignor to
Pomilio Corporation Limited, London, England,
a company of England

Application April 7, 1939, Serial No. 266,691
In Great Britain April 9, 1938

6 Claims. (Cl. 204—280)

This invention is for improvements in or relating to electrolytic cells.

The anodes in electrolytic cells, employed for the production of alkali from a sodium chloride solution, are usually formed from artificially prepared graphite which is of a porous character. Difficulty arises in forming a good electric connection between such porous anodes and an electric conductor or busbar. Various methods of forming a connection have been proposed, for example, by forming a smooth surface contact between the graphite and the metal of the conductor or by the interposition of a wire sheet between the two parts which are clamped together under pressure. In most instances, however, after a certain lapse of time, the chlorine liberated at the anodes finds its way by capillary attraction through the porous graphite to the joint and attacks the metallic parts of the connection. In order to avoid this capillary action, the anodes have been impregnated with oils, waxes, etc., but although this reduces the porous quality of the anode, it does not entirely eliminate it. For example, it has been proposed, in an electrolytic cell in which vertical bars of gas carbon are employed as the electrodes, to secure their lower ends to a holder by means of carbon pins which are passed through holes in the holder into taper holes in the vertical bars. The portion of the electrode which surrounds the pin was impregnated with paraffin and the pin itself was similarly impregnated. The pins were connected to an electric lead. Such forms of joints, however, were found not entirely to avoid creeping of the electrolyte.

It has now been found that capillary flow will not take place across a joint formed between two separate graphite parts in contact. Thus, according to this invention, there is secured in contact with the graphite anode, above the level of the electrolyte, a separate graphite part arranged for connection with the electric conductor or busbar. For example, the upper part of the graphite electrode may be provided with one or more taper holes into which are inserted one or more graphite plugs provided with mercury cups into which the electric conductor or busbar projects.

The following is a description of an electrolytic cell suitable for decomposing a common salt solution resulting in the production of chlorine gas and caustic soda solution, reference being made to the accompanying drawing, in which—

Figure 1 is an end elevation of a cell;

Figure 2 is a cross section of the cell shown in Figure 1.

The main body 10 of the cell is formed from concrete or cement and is long and narrow as compared with its height. Each wide side wall is provided with a rectangular opening which extends along the greater part of the width of the wall. The margin of each opening is recessed to provide a shoulder 11. The space 12 within the main body of the cell constitutes an anode chamber into which extends a number of carbon anodes 13. The cathode chamber comprises an outer sheet-metal wall 14 to which is secured and spaced away therefrom an inner perforated sheet-metal wall 15. Stretched across the inner face of the perforated metal wall is a sheet of open-mesh asbestos fabric 16 which is secured in position by a non-corrodible metal wire 9 which is threaded through the margin of the asbestos fabric and wound around pegs 17 secured to the outer sheet-metal wall 14. The aforesaid shoulders 11 are lined with rubber strips 18 against which a porous diaphragm of asbestos cardboard 19 is laid. The cathode chamber is shaped to fit the opening in the side wall of the cell and to abut against the asbestos sheet diaphragm and is held in place by a number of clamps 20 secured to the side of the cell.

The cathode compartment which is of considerable weight may be suspended from an overhead girder 21 by suspension members 22 which are secured at one end to said girder and at the other end to the outer wall of the cathode compartment. The girder 21 may also be arranged to support the busbar 44 and electrical conductors 45 hereinafter referred to.

The bottom of the cell is mounted on electric insulators 23 which rest on the top of foundation blocks 24.

In order to prevent the electrolyte from creeping by capillary action along the anodes to the electrical connections, each of the graphite anodes 13 is provided at its upper end with a tapered hole 42 which receives a taper plug 43 having a cup formed therein for receiving mercury. The electrical conductor comprises a busbar 44 from which depends a number of leads 45 each of which dips into a mercury cup. The busbar 44 may be suspended from the overhead girder 21 through suitable insulating means. The lower ends of the anodes may be supported on the bottom of the cells by earthenware distance-pieces 49.

I claim:

1. The combination with an electrolytic cell having a porous graphite anode adjacent which is liberated an element corrosive to common met-

als and capable of permeating said anode by capillary attraction, and a container enclosing the cell, said anode projecting outwardly through said container thereby presenting exteriorly a portion not subject to direct contact with said element, of a terminal including a graphite member entirely outside of said cell and normally in conducting engagement with the exterior portion of said anode only but separable therefrom, providing a joint therebetween impervious to capillary flow of said element, and a metallic conductor in conducting engagement with said member.

2. The apparatus defined by claim 1 characterized by said member being a tapered plug fitting in a tapered hole in the outwardly projecting portion of said anode.

3. The apparatus defined by claim 1 characterized by said member having a recess with mercury therein into which a metallic conductor dips.

4. The combination with an electrolytic cell having a porous graphite anode adjacent which is liberated an element corrosive to common metals and capable of permeating said anode by capillary attraction, and a container enclosing the cell, said anode projecting outwardly through said container, a graphite connecting piece in contact with the projecting portion only of the anode over a substantial area thereof outside said container, said connecting piece having provision for the connection thereto of an electric conductor.

5. The combination with an electrolytic cell having a porous graphite anode adjacent which is liberated an element corrosive to common metals and capable of permeating said anode by capillary attraction, and a container enclosing the cell, said anode being disposed in the cell with one end projecting out through the upper wall of said container, the exposed end of the anode having a conical socket formed therein and a conical graphite plug in said socket providing a surface contact with the anode over a substantial area and having provision for the connection of an electric conductor thereto.

6. The combination with a plurality of electrolytic cells each having a porous graphite anode adjacent which is liberated an element corrosive to common metals and capable of permeating said anode by capillary attraction, and a container enclosing the cell, one end of each anode projecting out through the upper wall of its container, the projecting end of each anode having a conical socket, a conical graphite plug in each socket providing a substantial area of contact with said anode and having a recess therein, a busbar extending adjacent the projecting portions of said anodes and a metal conductor extending from the bus bar into the recess of each plug.

UMBERTO POMILIO.
